[57] **CLAIM**

The ornamental design for a binocular hood, as shown and described.

DESCRIPTION

FIG. 1 is a front isometric view of a binocular hood showing my new design.

FIG. 2 is a right side elevational view thereof, the left side view being identical.

FIG. 3 is a top plan view thereof.

FIG. 4 is a bottom plan view thereof.

FIG. 5 is a rear elevational view thereof.

FIG. 6 is a front elevational view thereof.

FIG. 7 is a front isometric view of an alternative embodiment of the binocular hood showing my new design.

FIG. 8 is a right side elevational view thereof, the left side view being identical.

FIG. 9 is a top plan view thereof.

FIG. 10 is a bottom plan view thereof.

FIG. 11 is a rear elevational view thereof; and,

FIG. 12 is a front elevational view thereof.
